[57] CLAIM

The ornamental design for a vacuum cleaner, as shown and described.

DESCRIPTION

FIG. 1 is a perspective view of a vacuum cleaner showing our new design;

FIG. 2 is a rear elevational view thereof;

FIG. 3 is a side elevational view of the opposite side of FIG. 1;

FIG. 4 is a front elevational view thereof;

FIG. 5 is a top plan view thereof; and,

FIG. 6 is a bottom plan view thereof.

The handle shown in broken lines in FIGS. 1-6 is for illustrative purposes only and forms no part of the claimed design.
